PRINTING PRESS

Montgomery O. Jones and Wesley P. Shomaker, Richmond, Va.

Application March 2, 1933, Serial No. 659,310

9 Claims. (Cl. 164—99)

This invention relates to improvements in printing presses of the type used in the printing of church contribution envelopes and the like of the type known as the duplex envelope. Such envelopes are divided into two pockets by means of a transverse row of perforations.

In the Jones and Shomaker Patent No. 1,855,132, there is disclosed feeding mechanism for supplying envelopes to a printing press which comprises an endless row of magazines from which envelopes are successively withdrawn and delivered to the press. This apparatus is designed primarily for use in printing church contribution envelopes and the like which are furnished to contributors in identical sets except for an identifying number, each envelope of a set bearing the date upon which it is intended that the envelope shall be used. It is often desirable to interpose in the sets of envelopes special envelopes as to which the row of perforations is undesired. Heretofore, it has been customary to insert these special envelopes by hand into the groups of envelopes which have passed through the printing press.

An object of the present invention is the provision of means for rendering the perforator operative as desired, thereby permitting special envelopes to be arranged in the magazines and be handled by the machine in the same manner as the other envelopes except that the special envelopes are not perforated, so that such special envelopes are properly arranged in each group of envelopes as the same is discharged from the printing press.

Other objects, novel features and advantages of this invention will be apparent from the following specification and accompanying drawings, wherein:

Fig. 1 is a plan view of a device embodying the invention;

Fig. 2 is a section on the line 2—2 of Fig. 1;

Fig. 3 is an enlarged fragmentary section similar to Fig. 2 and with the elements in a different position, and

Fig. 4 is a detailed view of a portion of the perforator actuating mechanism.

As disclosed in detail in the above mentioned Jones and Shomaker patent, a plurality of vertical magazines 10 are carried by a chain 11 and are moved horizontally by mechanisms not shown. Each magazine contains a stack of envelopes or the like. A suction block 12 is reciprocated vertically by mechanism not shown and removes the bottom envelope from each magazine in succession and an oscillating picker 13 transfers the

envelope from the suction block 12 to the table 14 from which it is pushed between feed rollers 15 by fingers 16. The above mechanism is disclosed in detail in said Jones and Shomaker patent and is therefore not described further in this application.

The rollers 15 feed the envelopes in succession between a printing cylinder 17 and impression cylinder 18. The cylinder 17 is journaled on a sleeve 19 eccentrically fixed to a shaft 20, whereby rotation of said shaft is effective to move the printing cylinder toward and away from the impression cylinder. This arrangement is described in detail in Jones and Shomaker Patent No. 1,894,044. The impression cylinder 18 carries an envelope held by an automatically operated gripper 18a past a perforator 21 by means of which the envelope is provided with a transverse row of perforations after which it is removed from the impression cylinder by a stripper 22 and delivered between belt conveyors 23 and 24 by which it is discharged from the press.

The perforator 21 is carried by a shaft 25 arranged in slots 26 in the parallel arms 27 of a bracket 28. The shaft 25 is slidable in the slots 26 to move the perforator toward and away from the impression cylinder 18. The arms 27 of the brackets 28 are provided with recesses terminating in shoulders 29 and plate 30 are arranged in said recesses and have apertures through which extend the ends of the shaft 25. The plates 30 are provided with surfaces 31 and 32 adapted in different positions of the plates to engage the shoulders 29. The surfaces are so arranged that when the surfaces 31 are in contact with the shoulders 29 the perforator is out of engagement with the impression cylinder and when the surfaces 32 are in contact with the shoulders 29, the perforator engages the impression cylinder. A spring 34 tends to draw the plates into the position in which the surfaces 31 engage the shoulders 29.

Arms 35 carried by a shaft 36 are provided to move the plates 30 into the position in which the surfaces 32 engage the shoulders 29 and hold the plates in such position with the perforator in engagement with the impression cylinder (Fig. 1). A spring 37 is connected to the free end of an arm 38 carried by the shaft 36 and maintains the arms 35 in the position shown in Fig. 2 with the perforator in contact with the impression cylinder, the spring 37 being stronger than the spring 34.

An arm 39 is connected to the end of the shaft 36 and has a link 40 connected to its free end. 55

The link 40 is also connected to an arm 41 carried by a post 42 rotatably supported adjacent the chain 11. The post 42 is provided with an arm 43 which extends into the path of a pin 44 carried by the chain 11. The pin 44 is removably carried by the chain 11 and has a recess in its upper end into which projects the lower end of a pintle 11a connecting together links of the chain 11.

10 Means, (not shown) are provided for driving one or more of the shafts around which the conveyors 23 and 24 are passed. The shaft 25 carries a pulley 45 and the inner shaft for the conveyor 23 also carries a pulley 46 and an extensible belt 47 is trained around these two pulleys so that the perforator 21 is rotated at the same peripheral speed as the impression cylinder 18. By having the perforator 21 rotating at the same peripheral speed as the impression cylinder, 15 any possibility of tearing an envelope upon the return of the perforator to operative position is avoided.

In the operation of the machine, certain of the magazines contain envelopes which are not to be 20 perforated and pins 44 are attached to the chain at proper places to render the perforator inoperative with respect to such envelopes. Normally, envelopes are withdrawn from the magazines and passed between the perforator and the impression 25 cylinder to form a row of perforations. The perforator is held in operative relation to the impression cylinder by reason of the surfaces 32 being in engagement with the shoulders 29, due to the fact that the plates 30 are held elevated by the 30 arms 35 under the influence of the spring 37, (see Fig. 1). However, upon engagement of the pin 44 with the arm 43, the post 42 is rotated and the link 40 pulled to rotate the shaft 36, in a direction to move the arm 35 downwardly, thereby permitting the spring 34 to draw the plates 30 from the position shown in Fig. 2 to the position shown in Fig. 3. The perforator is thereby moved away from the impression cylinder and the envelope passing through the printing press at this time 45 is not perforated. As soon as the pin 44 passes out of contact with the arm 43, the spring 37 rotates the shaft 36 to its original position and the arm 35 moves the plate 30 back into the position shown in Fig. 2, thus bringing the perforator 50 back into operative relation to the impression cylinder.

As many pins 44 may be used as there are magazines containing envelopes not to be perforated and these pins are arranged on the chain at the 55 proper points to trip the perforator at such time as one of these envelopes is passing through the press. In this way, the special envelopes are handled similar to the other envelopes and are properly arranged in each group of envelopes as the 60 group is discharged from the printing press. Manual insertion of special envelopes in the sets of envelopes is thus avoided.

Other parts of the printing press may be actuated or rendered inoperative by mechanism actuated by pins carried by the chain 11. There may, therefore, be provided a plurality of collars 46 65 rotatably supported upon a base 46a and having arms projecting into the path of pins 44a carried by the chain 11, (Fig. 4). The collars are also 70 provided with additional arms 48 suitably connected with the parts of the press to be controlled.

Usually, the parts above referred to are not intended to be operated at the same time and therefore the arms 47 are operable at different times. 75 For this reason, the pins 44a are provided with

notches in alignment with the arms 47 not to be actuated by the particular pins. In this way, selective operation of the various parts is provided for.

It is of course understood that various modifications may be made in the apparatus above described, without in any way departing from the spirit of the invention as defined in the appended claims.

We claim:

1. In a printing press, an impression cylinder, a perforator cooperating therewith, means to feed envelopes or the like between the cylinder and perforator, and means controlled by said feeding means for temporarily moving said perforator out of operative relation to the cylinder.

2. In a printing press, an impression cylinder, a perforator cooperating therewith, means for feeding envelopes or the like between said perforator and cylinder, means for maintaining said perforator in operative relation to said cylinder, resilient means tending to move said perforator out of operative relation to the cylinder, and means actuated by said feeding mechanism for temporarily rendering said maintaining means 25 inoperative.

3. In a printing press, an impression cylinder, a perforator cooperating therewith, a movable endless row of magazines, means for withdrawing envelopes or the like from successive magazines and feeding the same between said cylinder and perforator, and means controlled by said row of magazines for temporarily moving said perforator out of operative relation to the impression cylinder.

4. In a printing press, an impression cylinder, a perforator cooperating therewith, a movable endless row of magazines, means for withdrawing envelopes or the like from successive magazines and feeding the same between said cylinder and perforator, resilient means tending to move said perforator away from said cylinder, means for holding said perforator in operative relation to said cylinder, and means actuated by said row of magazines for temporarily rendering said holding means inoperative.

5. In a printing press, an impression cylinder, a perforator cooperating therewith, a movable endless row of magazines, means for withdrawing envelopes or the like from successive magazines and feeding the same between said cylinder and perforator, means supporting said perforator for movement toward and away from said cylinder, resilient means tending to move said perforator away from said cylinder, means for holding said perforator in operative relation to said cylinder, and means actuated by said row of magazines for temporarily rendering said holding means inoperative.

6. In a printing press, an impression cylinder, a perforator cooperating therewith, a movable endless row of magazines, means for withdrawing envelopes or the like from successive magazines and feeding the same between said cylinder and perforator, and automatic trip actuated means timed with movement of said magazines for temporarily moving said perforator out of operative relation to the impression cylinder.

7. In a printing press, an impression cylinder, a perforator cooperating therewith, a movable endless row of magazines, means for withdrawing envelopes or the like from successive magazines and feeding the same between said cylinder and perforator, resilient means tending to move said perforator away from said cylinder, means 75

for holding said perforator in operative relation to said cylinder, and means timed with movement of the magazines for momentarily rendering said holding means inoperative.

- 5 8. In a printing press, an impression cylinder, a perforator normally in co-operative relation therewith, a movable endless row of magazines, means for withdrawing envelopes or the like from successive magazines and feeding the same between said cylinder and perforator, and means timed with the movement of said magazines for moving said perforator out of and back to normal position.
- 10 10

9. In a printing press, an impression cylinder a perforator supported in operative relation thereto and movable out of operative relation, a movable endless row of magazines, means for withdrawing envelopes or the like from successive magazines and feeding the same between said cylinder and perforator, and means timed with the movement of said magazines for temporarily moving said perforator out of operative relation to said cylinder.
